UNITED STATES PATENT OFFICE.

EDMUND O. SCHWEITZER, OF CHICAGO, ILLINOIS.

FUSE DEVICE.

1,279,020.

Specification of Letters Patent. Patented Sept. 17, 1918.

Original application filed April 21, 1913, Serial No. 762,463. Divided and this application filed January 16, 1914. Serial No. 812,369.

To all whom it may concern:

Be it known that I, EDMUND O. SCHWEITZER, a citizen of the United States, residing at Chicago, in the county of Cook and State 5 of Illinois, having invented a certain new and useful Improvement in Fuse Devices, of which the following is a full, clear, concise, and exact description, reference being had to the accompanying drawings, forming 10 a part of this specification.

My invention relates to fuse devices.

Prominent objects of the invention are to provide a simple, practical, and efficient type of fuse device, to secure a high degree of 15 sensitivity and accuracy; to secure reliability of operation; and to secure the foregoing and other desirable results in a simple and expeditious manner.

In the accompanying drawings I show my 20 invention applied to apparatus for controlling a 3-phase system, but it will be understood that the invention can be applied to other apparatus and in other ways.

In the accompanying drawings, Figure 1 25 is a view illustrating a multiphase system and a motor therein, and a circuit opening arrangement having fuse devices embodying my present invention;

Fig. 2 is a view of the fuse itself; 30 Figs. 3, 4 and 5 are views of modified forms of fuse devices; and

Fig. 6 is a view similar to Fig. 1 of a modified arrangement of the invention.

In the accompanying drawings, and especially in Figs. 1 and 2, a 3-phase system with conductors 1, 2 and 3 is shown, said conductors leading to a motor 4. In each of the conductors 1, 2 and 3 are located fuses 5, 5^a and 5^b, which may be the ordinary type of 40 fuse adapted to operate or blow in the usual way upon an overload in the circuit conductors in which said fuses are respectively located. I also show heating coils 6, 6^a, and 6^b of resistance wire wound about the several 45 fuses 5, 5^a and 5^b. These heating coils 6, 6^a and 6^b are of sufficiently fine and high resistance wire to generate sufficient heat to melt or operate the fuses 5, 5^a and 5^b, upon a predetermined overload current flowing in 50 said coils, 6, 6^a, and 6^b. The coils 6, 6^a, and 6^b, are preferably connected so as to receive current from the circuits or conductors other than the circuits or conductors containing the fuses which said coils respectively in-

clude. As one arrangement I show in Fig. 1 55 the coil 6 for the fuse 5 in conductor 1 connected by conductors 7 and 8 in shunt with conductor 3; the coil 6^a for fuse 5^a included by conductors 9 and 10 in shunt with conductor 1 and also coil 6^b for fuse 5^b connected 60 by conductors 11 and 12 in shunt with conductor 2. Thus the fuse 5, for example, may be operated by an overload current in conductor 2 because of the coil 6 receiving current from the circuit including conductor 2. 65 Similarly fuse 5^a may be operated by an overload current in conductor 2, and also an overload current in conductor 1, and also fuse 5^b may be operated by an overload current in conductor 3, and also by an overload 70 current in conductor 2. Thus it will be seen that if for example an overload current in conductor 1 should operate or blow fuse 5, but the other conductors 2 and 3 of the system were not receiving sufficient overload 75 current to blow the fuses 5^a and 5^b, respectively, as for example where said fuses take more current than they should, as sometimes happens, the overload current in conductor 1 would to some extent persist notwithstanding 80 the blowing of the fuse 5, and would pass by conductors 9 and 10 through coil 6^a and thereby produce a heating effect upon fuse 5^a in conductor 2, which heating effect together with the load in fuse 5^a would operate 85 the latter, and thereby cut out the motor. Thus the entire system would be fully protected by the operation of the fuses in connection with the coils 6, 6^a and 6^b, it being understood that the latter are sufficiently 90 fine to burn out when the fuses with which they are associated have operated. Thus it will be seen that full protection may be accorded to apparatus on 3-phase or polyphase systems, and so serious damage and injury 95 may be prevented upon such systems where previously it has occurred by reason of the operation of the fuse in one line and the failure of the fuses in the other lines to operate.

In Fig. 2 I show one way in which the 100 fuses 5, 5^a and 5^b may be associated with the coils 6, 6^a, and 6^b. Fig. 2 shows a fuse of more or less usual type having apertures or slots 14 and 15 for connection with binding posts or terminals and a coil of wire 6 wound about said fuse and especially the middle portion thereof, layers 16 of mica or other material being placed on opposite sides of 105

the fuse to accommodate the wire windings. In Fig. 6 I show a 3-phase system similar to that shown in Fig. 1, but in this arrangement the coils 6, 6^a and 6^b are connected somewhat differently. For example these coils 6, 6^a and 6^b are connected by conductors 18, 19 and 20 in a series parallel arrangement with themselves and the line conductors 1, 2 and 3, as shown.

10 In Figs. 3, 4 and 5 are shown arrangements by which the invention may be applied to inclosed fuses. In Fig. 3, for example, is a cylindric inclosed fuse 21 having a cylindric sleeve or housing 22 applied to it, 15 a heating coil for melting the inclosed fuse being arranged in or carried by the sleeve 22, the ends of said coil being connected by conductors 23 and 24.

In Fig. 4 I show an inclosed fuse 25, in 20 which the interior fuse proper 26 is surrounded by a heating coil 27, from which connecting conductors 28 and 29 are extended.

In Fig. 5 I show an inclosed fuse 30 containing a glass tube 31 in which a fuse 32 is extended, the glass tube 31 being surrounded by a heating coil 33, to which connection may be made by conductors 34 and 35.

It will be understood that my invention 30 may be applied and used in ways other than those shown herein, and that changes and

modifications can be made in the structure herein without departing from the spirit of the invention.

This application is a division of my application Serial No. 762,463, filed April 21, 1913.

What I claim is:

1. A cartridge fuse having an insulating casing provided with ferrules and having a heating element arranged within said casing, said heating element having terminals passing through said insulating casing.

2. An externally controlled fusible cut-out having a casing of insulating material provided with annular terminals and supplementary terminals passing through the extremities of said casing.

3. A cartridge fuse having a casing provided with ferrules and also having a fuse link extending between the ferrules and a heating coil surrounding the fuse link between the ferrules, the ends of the heating coil being extended through the shell or casing of the device between the ferrules.

In witness whereof, I hereunto subscribe my name this 23rd day of December, A. D. 1913.

EDMUND O. SCHWEITZER.

Witnesses:

A. L. JONES,

H. A. JONES.
